UNITED STATES PATENT OFFICE.

PETER F. JOHNSON, OF OAKLAND, CALIFORNIA.

HAMMER GAUGE.

1,419,567.

Specification of Letters Patent. Patented June 13, 1922.

Application filed September 7, 1920. Serial No. 408,683.

To all whom it may concern:

Be it known that I, PETER F. JOHNSON, a citizen of the United States, residing at Oakland, in the county of Alameda, State of California, have invented a new and useful Hammer Gauge, of which the following is a specification in such full and clear terms as will enable those skilled in the art to construct and use the same.

10 This invention relates to a hammer gauge, and its object is to provide a gauge which is capable of being concealed within the hammer handle and which may be extended for use to enable the workman to space shingles or nails at any desired distance, while the gauge is made of a flexible material which will not in any way interfere with the use of the hammer so that it may remain extended while the hammer is in use.

15 Other objects of the invention will appear as the description proceeds.

An embodiment of the invention is shown in the accompanying drawings in which the same reference numeral is applied to the 25 same portion throughout, but I am aware that there may be modifications thereof.

Figure 1 is a side elevation of a hammer illustrating the use of the gauge and showing the gauge partly extended from the 30 hammer handle.

Fig. 2 is a longitudinal sectional view of a portion of the hammer handle showing the gauge partly extended.

Fig. 3 is an end elevation of the hammer 35 handle.

Fig. 4 is a view of the retaining washer for securing the gauge in place in the hammer handle, a portion thereof being broken away to illustrate the manner of securing 40 the gauge in a given position.

The numeral 1 indicates the hammer handle which is secured in the usual way to the driving head 2. The hammer handle is provided with a hole 3 within which a 45 flexible rubber rod 4 is slidable.

The rubber rod is sufficiently stiff to act as a gauge, while at the same time it will bend and in no way interferes with the use of the hammer because it may be bent from 50 side to side.

In order to prevent the gauge from falling out of the opening in the hammer handle it has a washer 5 pressed thereon which may be set at different lengths from the end of 55 the gauge, or the gauge may be held in dif-

ferent adjustments by means of the spring lock 6. The spring lock is secured at the back of the retaining washer 7. The retaining washer is secured in the end of the handle by means of two screws 8 and 9, and 60 it has a peripheral notch as indicated at 10 through which the short end 11 of the pivot lock 6 projects.

The screws 8 and 9 serve to hold the washer in place and they cause it to bear 65 upon the lock 6 with sufficient force to enable said lock to hold the gauge rod in any given adjustment. The fixed end of this lock surrounds the screw 9, or it may be secured in any other suitable manner.

70 This gauge is used where a considerable number of measurements of a fixed definite length are to be repeatedly made in conjunction with the tool to which the gauge is applied, and the gauge is of such a nature as 75 to permit it to be continuously extended without interfering with the work of the operator. When used in conjunction with a striking tool, a hole is bored in the handle of the tool and the scale of the gauge is made 80 to read a certain number of inches in conjunction with the length of the tool to which the gauge is applied. The gauge is pulled out from the tool handle the desired amount and locked in any given position by the 85 spring 11 whereupon the total length of the tool and gauge may be used for repeated measurements without retracting the gauge each time.

86 The gauge is also especially useful where 90 a series of short measurements are to be made, as for example: when a workman is laying shingles it is desirable to have a convenient method of measuring four inches each time a shingle is to be laid; therefore, 95 the gauge would be extended from the handle of the implement with which it is used four inches, and this would provide a shoulder to be placed against the shingle already nailed in place and give the definite 100 measurement for the next shingle, and without retracting the gauge the implement can be used for driving the nails in place, the gauge not in any way interfering with the implement because of its flexibility.

105 It will also be seen that the gauge may be used in the manner just mentioned or in conjunction with the length of the tool to which it is secured as above mentioned.

110 What I claim is as follows, but various

modifications may be made in the construction shown in the drawings and above particularly described form, within the purview of my invention.

- 5 In a measuring scale the combination with a tool handle, of a flexible gauge slidable thereinto, a washer on the end of the handle

through which the gauge slides, and a spring carried by said washer and adapted to bear upon the gauge to hold it in any desired 10 adjustment.

In testimony whereof I have hereunto set my hand this 16 day of July, A. D. 1920.

PETER F. JOHNSON.
